UNITED STATES PATENT OFFICE.

LOUIS EARL RICE, OF SALEM, OHIO, ASSIGNOR TO THE SILVER MANUFACTURING COMPANY, A CORPORATION OF OHIO.

AUTOMATIC DRILLING-MACHINE.

No. 857,538.

Specification of Letters Patent.

Patented June 18, 1907.

Application filed August 1, 1905. Serial No. 272,201.

To all whom it may concern:

Be it known that I, LOUIS EARL RICE, a citizen of the United States, residing at Salem, county of Columbiana, and State of Ohio, have invented certain new and useful Improvements in Automatic Drilling-Machines, of which the following is a specification.

My invention relates generally to drilling machines and as herein embodied is designed to produce a machine of this class, which after being set or given the necessary preliminary adjustment, in accordance with the requirements of the work, will thereafter operate automatically, requiring only that the work be secured in position and removed when completed.

The object of the invention is to insure uniformity and greater accuracy in the work produced, also to increase the output of the machine and at the same time effect a saving in both time and labor, by dispensing with the constant attendance of a skilled workman.

The accompanying drawings will serve to illustrate a machine suitable for carrying my invention into effect. I wish it understood, however, that I do not limit myself to either the construction or arrangement of the mechanism shown, as various changes may be made therein or other forms of mechanism employed operating in substantially the same manner to produce practically the same result.

In the drawings: Figure 1, is a view in side elevation of a drilling machine, constructed in accordance with my invention. Fig. 2, is a view in front elevation, thereof. Fig. 3, is a plan view partly in section. Fig. 4, is an enlarged detail view partly in section, showing the feed mechanism by which the drill spindle is advanced relatively to the work. Fig. 5, is a detail view of one of the speed changing gears, and Fig. 6, illustrates the trip latch in detail.

Referring now to the drawings: 1, represents a frame designed to provide support for the various parts of the machine. The frame is carried by a column 2, supported by a step 3, and mounted upon the column, there is a vertically adjustable swing-table 4. The table may be raised and lowered by means of an attached chain 5, running over a pulley 6, and winding upon a shaft 7, which is ordinarily rotated by a removable crank

(not shown) and locked by a pawl and ratchet or other suitable device 8.

The drill spindle 9 is mounted in bearings 10, and is connected to receive motion from a drive shaft 11, through a train of changeable speed gears 12, 13, 14, 15, 16 and 17. The shaft 11, carries fast and loose pulleys 18, 19, and is driven by a belt in the usual manner. The gears 12 and 13, are mounted to rotate independently upon the shaft 11, and are each provided with a key 20, movable in and out of engagement with a key-way 21 formed therein. Each of the keys terminates in a projecting knob or button 22, for convenience in adjusting the same and they are held in either of two positions of adjustment that is, in or out of engagement with the key-way of the shaft, by a spring pressed ball or pin 23, which co-operates with twin seats or recesses 24, 24, formed therein as shown in Fig. 5. Either of the gears 12, or 13, may therefore be secured to rotate with the shaft.

The gears 14 and 15, loosely mounted upon a stud shaft 25, are provided with interlocking projections 26, such for example as shown upon the gear 12, in Fig. 5, or they may be otherwise connected to rotate together and are driven by either the gear 12 or 13, depending upon which of these gears is locked to the drive shaft.

From the gear 14 motion is transmitted to the spindle through the bevel gears 16 and 17. The gear 16, turns loosely upon a stud shaft 27 and has spur teeth 28, formed thereon as shown in Fig. 3, to mesh with the gear 14. The gear 17 is keyed or otherwise connected to drive the spindle and at the same time permit end-wise movement thereof as required in advancing and retracting the drill relatively to the work upon the table 4.

When the spindle is to be driven at low speed motion is transmitted through the gear 12, the key of which is adjusted to interlock with the key-way in the shaft 11, while the gear 13 turns loosely thereon. For medium speed, the gear 13 is caused to act as the driver by being similarly keyed to the shaft and the gear 12 turns idly. For fast speed, the gears 12 and 15, are interchanged, the gear 15, being provided for this purpose with an adjustable key as shown in Figs. 1 and 3 to lock the same upon the shaft and the gear 12 with projections 26, to interlock with and rotate the gear 14.

Connected to the spindle at its upper end there is a feed screw 29, with which a split feed nut 30 co-operates as shown in detail in Fig. 4. The parts or members of the feed nut are carried by links 31, pivotally secured at one end thereof to a sleeve 32, and provided at the opposite end with studs or projections 33, entering cam slots 34, in a second sleeve 35. As arranged, these parts, that is, the link-connected sleeves and the interposed feed nut are designed to rotate together, motion being given the same by suitable gearing, such as the worm wheel 36 and worm 37, mounted to be driven from the shaft 11, by a belt passing around cone pulleys 38, 39.

In order that the advance of the drill or other tool under the action of the feed may be predetermined and automatically controlled, I provide means for periodically throwing the feed in and out of operation at definite points in the travel of the spindle. Mechanism suitable for this purpose will now be described.

As shown in Fig. 4, the sleeve 35, is provided with an annular groove 40, to receive the forked end of an arm 41, pivoted upon a pin 42. Thus arranged, the sleeve 35, is given motion lengthwise of the spindle, when the arm 41, is rocked, causing the cam slots 34, in the sleeve to co-act with the links 31, and move the members of the split feed nut carried thereby in and out of engagement with the threaded portion of the spindle. A lever 43, loosely mounted upon the pivot pin 42 of the arm 41, is connected with the free end of the latter by an eye-bolt 44. The bolt extends through a lug 45 on the lever and encircling its projecting end and held thereon by a nut 46, there is a spring 47, which acts upon the arm 41, tending normally to move its forked end downward and throw in the feed. As will be seen the adjustment of the feed is controlled by the lever 41, which is adapted to be operated either by hand or power. For convenience in shifting the lever by hand, its free end projects toward the front of the machine and is shaped to be conveniently grasped by the operator. At the opposite end of the lever, there is an automatic trip latch 48, which is pivoted thereon at 49. The latch, as shown in detail in Fig. 6, is provided upon one side with the lugs 50, 50, and upon the opposite side with a pin or stud 51, which projects through an elongated opening 52, in the lever and is normally held about centrally thereof by two pivoted fingers 53, 53, spring held against a stop lug 54. Co-operating with the latch, there is a trip-pin 55, carried by a rocker-arm 56. The rocker-arm is mounted free to turn upon the pin 42 and is connected through a rod 57, to receive motion from an eccentric 58, upon the drive shaft 11. The trip-pin 55, projects through an opening 59, in the frame 1, and terminates

adjacent to the latch, the arrangement being such that normally, or when the feed is thrown in, as shown in Fig. 4, the path of movement of the trip-pin is in line with the upper lug of the latch and strikes the same lightly on the up stroke without imparting motion thereto, clearing the lower lug on the down stroke.

The adjustment of the latch 48 relatively to the trip-pin, is effected automatically by means of a device shown in Fig. 1. This device consists of a gage-bar 60, which is connected through a right angle lever 61 and link 62 with the projecting end of the latch-pin 51. The bar 60, is slotted at 63, and fitted in the slot thereof, there are two stop buttons 64, 64, the relative position or spacing of which determines the travel or movement of the drill spindle as will be later on described. The buttons are adjustable and may be secured at any point in the slot in the bar, thus enabling the operator to place the same definitely in the preliminary adjustment of the machine in accordance with the requirements of the work.

A lever 65, co-acting with the stop-buttons serves to impart the required motion to the bar to shift the latch. The lever 65 is pivoted upon the frame at 66, and connected by links 67, to receive motion from the drill spindle, as it is fed downward to advance the tool to the work. At its free end, the lever terminates in a handle 68, which projects forward within convenient reach of the operator and at the opposite end, a spring 69, is attached thereto, acting through the lever and connecting links 67 to return the spindle to its normal position, when the feed is thrown out.

As a means of retaining the feed mechanism in position as adjusted, a spring pressed locking arm 70, is employed in connection with the lever 43, and serves to yieldingly hold the same against play.

The operation will be generally understood from the foregoing description and I will therefore describe the same briefly.

Assuming that the gearing is properly adjusted to drive the drill spindle at the required speed, the feed is thrown out by moving the lever 43, upward and the spindle is then lowered by means of the lever 65, until the drill or other tool reaches the point where it is to begin work. The upper stop button 64, is next adjusted until it rests upon the lever 65, and is locked in this position, thus limiting the upward travel of the drill at this point. The spindle is then moved downward until the tool rests upon the table 4, or to a point where the work is completed and the lower stop button 64, is adjusted relatively to the lever 65, thus fixing the lower point of travel of the spindle. These points having been determined to suit the work and the buttons upon the gage bar being now

properly set, the next step is to start the drill in operation and as this is done, the feed is automatically thrown in by the action of the spring 69, and the spindle begins to feed

5 downward. As the lever 65 strikes the lower button of the gage bar, the latch 48, is shifted toward the right as viewed in Fig. 1 and the trip pin acts upon the lower lug thereof, and rocks the levers 41 and 43, throwing out the feed as above described and thereupon the spindle is instantly carried upward by the spring 69. In the return of the

10 spindle, the lever 65 moving with the same strikes the upper button of the gage bar and 15 through the connections described shifts the latch toward the left and the trip pin acting now upon the upper lug thereof, throws in the feed and thereafter the spindle continues to feed down and return automatically without requiring further attention, it being necessary to place and remove the work as above stated.

Having thus described my invention, I claim:

20 1. A drilling machine comprising a rotatable drill spindle, a tripping device, means for driving said spindle and said tripping device, feed mechanism for giving the spindle motion in the direction of its length, and 30 means for automatically connecting the tripping device with the feed mechanism for throwing the feed in and out of operation at predetermined points in the travel of the spindle.

35 2. A drilling machine comprising a rotatable drill spindle, a power shaft therefor, feed mechanism for giving the spindle motion in one direction only, a tripping device adapted to be continuously driven by said power shaft, and means for automatically connecting the tripping device with the feed mechanism for throwing the feed in and out of operation at predetermined points in the travel of the spindle.

40 3. A drilling machine comprising a rotatable drill spindle, a reciprocating tripping device, feed mechanism for giving the spindle motion in one direction only to advance it toward the work, a latch connected with said feed mechanism and normally clear of said tripping device, and means for automatically shifting the latch into the path of the tripping device for throwing the feed in and out of operation at predetermined points in the travel of the spindle.

45 4. A drilling machine comprising a rotatable drill spindle, a power shaft therefor, feed mechanism for advancing the spindle relatively to the work, means tending normally to retract the spindle, and means arranged to be continuously operated by the power shaft and means whereby said continuously operated means may be connected to the feed mechanism for throwing the feed

into and out of operation to limit the movement of the spindle. 65

5. In a drilling machine, a rotatable drilling spindle, feed mechanism therefor, a power shaft, tripping mechanism arranged to be continuously operated by said power shaft, 70 for throwing the feed mechanism into and out of operation, a latch connected with said feed mechanism, a gage-bar having adjustable stops thereon connected to said latch, and means connected to the spindle and arranged to engage said stops. 75

6. The combination with feed mechanism, of a co-operating trip device comprising a trip pin, means for giving said pin a back and forth movement in a definite path of travel, a 80 co-operating latch normally clear of the trip pin and connected with said feed mechanism, and means for shifting the latch relatively to the pin.

7. The combination of a drill spindle, requisite gearing co-operating therewith, feed mechanism for giving the spindle motion in the direction of its length, means tending to retract said spindle, a trip device for engaging and disengaging the feed comprising a reciprocating trip pin, a co-operating latch connected with the feed mechanism, and means for periodically shifting the latch relatively to the pin to throw the feed in and out of operation at predetermined points in the path of 95 travel of the spindle.

8. The combination of a rotatable drill spindle, a power shaft therefor, a feed screw operatively connected with the spindle, a rotatable feed nut, a lever arm connected with 100 said feed nut, an automatic trip device adapted to be continuously operated by the power shaft, a latch carried by said lever, and means for periodically shifting the latch into the path of the trip device and causing the lever 105 arm to shift the nut into engagement with the feed screw.

9. The combination of a rotatable drill spindle, a feed screw operatively connected with the spindle, feed mechanism comprising 110 pivoted links and split feed nut members pivoted thereto, a cam-member connected with said links, a lever arm connected with said cam-member, a trip device, and means to periodically connect the lever arm with the 115 trip device.

10. An automatic feed mechanism comprising a feed screw, a rotary sectional feed nut, pivoted supports to which the members of the feed nut are pivotally secured, cams 120 co-acting to impart movement to the supports to shift the nut in and out of engagement with the feed screw, a lever for operating the cams, and an automatic trip latch controlling the lever. 125

11. An automatic feed mechanism comprising a feed screw, a loose sleeve thereon, a sectional feed nut co-operating with the feed

screw, links pivoted upon the sleeve and supporting the members of the feed nut, a second sleeve loosely mounted upon the feed screw and provided with cam portions engaging the links, and means for giving motion to the last named sleeve to effect an opening and closing of the feed nut relatively to the feed screw.

12. An automatic feed mechanism comprising a feed screw, a loose sleeve thereon, a sectional feed nut co-operating with the feed screw, links pivoted upon the sleeve and supporting the members of the feed nut, a second sleeve loosely mounted upon the feed screw

and provided with cam slots to receive the free ends of the links, means for rotating the link connected sleeves and the feed nut carried thereby, and means for producing relative motion between the sleeves lengthwise of the feed screw to cause the cam controlled links to open and close the feed nut.

In testimony whereof, I affix my signature, in the presence of two witnesses.

LOUIS EARL RICE.
